US00D540762S

(12) **United States Design Patent** (10) **Patent No.:** **US D540,762 S**
(45) **Date of Patent:** **** Apr. 17, 2007**

(54) **VIDEOCONFERENCE ENDPOINT**

(75) Inventor: **Finn Helge Lunde**, Asker (NO)

(73) Assignee: **Tandberg Telecom AS**, Lysaker (NO)

(**) Term: **14 Years**

(21) Appl. No.: **29/220,659**

(22) Filed: **Jan. 3, 2005**

(30) **Foreign Application Priority Data**

Jul. 5, 2004 (NO) 2004 0369

(51) **LOC (8) Cl.** **14-03**

(52) **U.S. Cl.** **D14/129; D14/125; D14/126**

(58) **Field of Classification Search** D14/125-135,
D14/239, 379, 371, 374, 375, 376, 113; D13/151,
D13/153; 312/7.2; 348/836, 838, 180, 184,
348/325, 739; 341/12; 248/917-924; 345/104,
345/133, 156, 168, 87, 173; 349/1, 2, 11,
349/62

See application file for complete search history.
